SHEET FEEDING AND REGISTERING MECHANISM FOR PRINTING-PRESSES.

1,108,220.

Specification of Letters Patent. Patented Aug. 25, 1914.

Application filed June 7, 1902. Serial No. 110,570.

To all whom it may concern:

Be it known that I, GEORGE E. PANCOAST, a citizen of the United States, and a resident of Brooklyn, in the county of Kings, State 5 of New York, have invented certain new and useful Improvements in Sheet Feeding and Registering Mechanism for Printing-PresSES, of which the following is a specification.

10 My invention relates to a sheet feeding and registering mechanism, and it has for an object to provide a mechanism whereby sheets of paper or similar material may be uniformly and reliably presented in accurate 15 register to high speed printing presses or similar machines.

In sheet presses it has been the common practice heretofore to present the sheets to a moving impression cylinder by means of 20 a stationary guide or front gage against which the forward edges of the sheets are placed by hand, or otherwise, the gage being moved out of the path of the sheets at the proper time to deliver them to the impression cylinder at the desired point thereon. According to this principle of operation 25 the sheets have to be instantly accelerated from a position of rest to the full speed of the impression cylinder, and it is found in 30 practice that more or less slippage or lost motion between the sheets and the grippers on the impression cylinder is inevitable. Heretofore, moreover, the grippers have 35 been so constructed that when coming into contact with the sheets they have a rearward motion relative to the impression cylinder, which motion is imparted more or less to the sheets, thereby causing the positions of the latter on the impression cylinder to vary. 40 For these reasons it has been impossible to secure perfect register in such presses especially at high speeds.

My invention has for an object to overcome the above mentioned difficulties and to 45 provide a sheet feed press in which a perfect register of the impressions on the sheets may be secured at high as well as low speeds.

My invention consists in the novel parts, 50 improvements and combinations herein shown and described.

The accompanying drawings, which are referred to herein and form a part hereof, 55 illustrate by way of example, two embodiments of my invention and serve in connection with the description herein to explain

the principles of my invention and the best mode in which I have contemplated applying those principles.

Of the drawings, Figure 1 represents a side elevation of a portion of a printing press constructed in accordance with my invention; Fig. 2 is a plan view of the same; Figs. 3 and 4 are respectively a plan and a sectional side view illustrating a detail; Figs. 5, 6 and 7 are sectional views of a portion of the press showing the positions assumed by certain of the parts at successive periods of their operation; Fig. 8 is a view similar to that of Fig. 1 illustrating a different form of construction; Fig. 9 is a transverse sectional view of the same; Fig. 10 is a plan view; and Figs. 11, 12 and 13 are end views illustrating the operation of the modified form of the device.

In accordance with my invention, the 75 sheets are presented to the press at substantially the same speed as that of the printing and impression members, and the position of the sheets with reference to the printing and impression surfaces is determined in the 80 press by suitable positioning devices, which are carried by or move with the grippers and with them have a suitable movement relatively to the sheet carrying member of the press for adjusting the sheets upon that 85 member before they are secured thereto by the grippers.

Referring to the drawings in detail, and at first to the form of the device shown in Figs. 1 to 7, 1 represents the impression 90 member of a printing couple, the impression member shown being in the form of a cylinder which is suitably journaled in a frame.

2. The sheets are supplied to the impression cylinder 1 from any suitable source, as from a web-cutter, or from a device for automatically separating the sheets from a pile, the sheet supplying device, whatever form is used, being timed as usual, to forward a sheet to the impression cylinder for every 100 printing revolution of the latter and to present the sheet as nearly as possible at the desired point on the impression cylinder. The sheets are advanced to the impression cylinder at substantially the same speed as 105 that of the cylinder by any suitable means, as by the feed rollers 3 and 4, of which the latter is positively driven from the gear 5 on the shaft of the impression cylinder by the intermediate gear 6 which meshes with 110

the gear 5 and also with a gear 7 fixed on the shaft of the roller 4. Tapes 8 or other suitable means, are provided to convey the sheets from the supply to the feed rollers 3 and 4 and the sheets are directed from the feed rollers onto the surface of the impression cylinder by the guide fingers 9 and 10.

In accordance with the construction shown, a transverse shaft 11 is journaled in the impression cylinder in advance of the forward edge of the impression surface 12 and is provided with a plurality of gripper fingers 13. Preferably and as shown, the gripper fingers 13 are arranged to co-operate with the upper surface of a member 14 to grip the forward edges of the sheets as they emerge from the guide fingers 9 and 10 and carry the same to the point of delivery. The member 14 is removably secured to the forward edge of the impression surface 12 by screws 15. The grippers are brought in a direction to grip the sheets by a suitable spring, (not shown) and they are opened to receive the sheets and deliver the same by cam 16 which is fixed to the frame 2 at one end of the cylinder in position to engage the arm 17 secured to one end of the shaft 11. For the purpose of accurately fixing the position of the sheets on the impression surface 12, suitable positioning or gaging devices are provided on the impression cylinder, said positioning devices being given a movement in the path of the sheets and in a backward direction with relation to the movement of the impression member so as to engage the forward edges of the sheets and bring said edges to a predetermined position with relation to the impression surface. In order that the position of the sheets may not be disturbed by the grippers as they close thereon, the positioning devices are caused to move with the grippers, the latter being to this end given a backward movement with relation to the impression cylinder as they approach the front edge of the sheets. Preferably the positioning devices are mounted directly on the grippers. As shown, the positioning devices consist of abutments or gages 18 which are adjustably secured to the inner side of the gripper fingers 13 by screws 19 which pass through slots in the gages and are tapped into the fingers. To prevent lateral displacement of the gages they are provided with pins 20 which engage slots in the fingers as shown. With the object in view of preventing displacement of the sheet on the gages the member 14 is provided with recesses 21 adapted to receive the gages. The operative faces of the gages 18 are preferably arranged at substantially right angles to the gripping surfaces of the fingers 13 so that when the grippers are opened to receive the sheets, the gages will be located across the paths of the sheets as they leave the guides 9 and 10 and so that

the gages will be inclined outwardly and forwardly with relation to the said path, as illustrated in Fig. 5. The operative surfaces of the gages and grippers will thus form a kind of recess into which the forward edges of the sheets will be directed by the guides 9 and 10. Owing to the position of the center of oscillation of the gripper fingers the operative surfaces of the latter together with the gages 18 will have a component of motion rearwardly with relation to the forward edge of the impression surface so that the forward edges of the sheets will be carried backward to a predetermined position with relation to the impression surface before they are clamped by the grippers. By reason of this construction any slight irregularity in the feed of the sheets will be compensated for. As the forward edges of the sheets are moved backwardly by the grippers and gages, a slight buckle or bend will be formed in the sheet between the points of the grippers and the forward ends of the guides 9 and 10 as illustrated in Fig. 6. As the sheet is carried forward and into contact with a printing surface, the slight buckle or bend formed in the sheet will be caused to travel back so that every portion of the sheet will occupy the same point on the impression cylinder that it would have occupied if it had been fed onto the impression surface with its forward edge in the proper predetermined position.

After the forward edge of the sheet has been carried past the printing surface, it is transferred from the grippers to a suitable delivery mechanism. The delivery mechanism shown consists of a series of stripper fingers 23 which are terminated at a point close to the surface of the impression cylinder and act to guide the sheets to a pair of suitable sheet-forwarding delivery rollers 24 and 25.

In order that the sheets may be positively controlled from the time they are released by the gripper fingers until they reach the rollers 24 and 25, a series of rollers 26 is provided between which and the impression surface 12 the sheets are nipped. The rollers 24 and 26, as shown, are mounted on suitable shafts journaled at their opposite ends in the members of arms 27 and 28 respectively, said arms being adjustably fixed to the transverse rod 29 secured at its opposite ends in suitable brackets 30. The roller 25 is mounted on a suitable shaft which is journaled at its opposite ends directly in the brackets 30.

For the purpose of lifting the forward edges of the sheets so that they may be engaged with certainty by the stripper fingers 23 suitable sheet lifters are provided. In accordance with the construction shown, the sheet lifters consist of a series of pins 30^a which are fixed in the lower ends of the

gages 18 and project forwardly under the sheets in such a position that when the grippers are opened to release the sheets, the ends of the pins 31 act to lift the forward edges of the sheets outwardly with relation to the impression surface as shown in Fig. 7. The member 12 is provided with recesses 30^b to accommodate the fingers 31. In accordance with the embodiment of my invention illustrated in Figs. 8 to 13 inclusive, a series of fingers 31 is rigidly secured to a pair of transverse rods or bars 32 and 33, and these bars are provided at their outer ends with suitable friction rollers, which are adapted to slide in the cam grooves 35 formed in the opposite ends of the cylinder. The movement of the bars 32 and 33, together with the fingers 31, is controlled by a pair of links 36, which are pivoted at their outer ends to the opposite ends of the bar 33 and are bifurcated at their inner ends to embrace and be guided by the shaft of the impression cylinder 1, said links being provided with stud rollers 37, adapted to engage the cams 38 fixed to the frame 2 in a suitable position with relation to the axis of the cylinder. As shown, the bars 32 and 33 are impelled inwardly toward the axis of the cylinder, so that the stud rollers 37 are held in constant engagement with the cam 38, by means of a spring 39. The cam grooves 35 are substantially radial at their inner portions and are curved forwardly at their outer ends, as shown. It follows from this construction that when the bars 32 and 33 are both in engagement with the inner ends of the slots 35, the fingers 31 will move in a radial direction with relation to the impression cylinder, and when the bars 32 and 33 are moved outwardly, the upper bar 32 will pass into the curved portion of the slot 35 and the fingers 31 will move away from the forward edge of the impression surface back into the gripper gap of the impression cylinder, as indicated in Fig. 11. The cams 38 are preferably provided with three eccentric portions 41, 42, 43, and three concentric portions 44, 45 and 46. The eccentric portion 41 acts to bring the fingers 31 into position against the forward edge of the impression surface, and the cam is so adjusted that this operation takes place at such time after the forward edge of the impression surface has passed the guides 9 and 10 that a bend or buckle will be formed in the sheets, the latter being fed to the impression surface with their forward edges a suitable distance in advance of the forward edge of the impression surface. This position of the fingers 31 is illustrated in Fig. 12. The fingers are preferably retained in this position for a short time by the concentric portion 44 of the cam to allow the forward edges of the sheets time to be adjusted

against the fingers, said adjustment being effected by the elasticity of the paper and the buckle therein. The outer rearwardly bent ends 31^a of the fingers 31 are then permitted to close upon and grip the forward edges of the sheets by the eccentric portion 42 of the cam, and the fingers are permitted to remain in this position by the low concentric portion 45 of the cam, so as to hold the sheets and carry them past the printing member to the point of delivery. The sheets are released and the fingers 31 are moved back to their inoperative position by the eccentric portion 43 of the cam, said fingers being held in that position by the high concentric portion 46. It will be seen that in this construction there is a fixed relation between the sheet-adjusting and sheet-holding devices, and further that the sheet-adjusting devices are moved in the path of the sheets and relatively to the sheet-carrying member to adjust the sheets, and that the sheet-holding or gripping devices, as they are brought into contact with the sheets move at right angles to the path of motion of the latter so that there can be no lost motion or slipping of the sheets due to the action of the gripping surfaces.

For the purpose of preventing the edges of the sheets from slipping inwardly along the inner surfaces of the fingers 31, recesses 34 are preferably provided in the forward edge of the impression surface in position to receive the fingers 31 when they are in their operative position. The edges of the sheets are prevented from slipping outwardly off the ends of the guide fingers 31 by the rearwardly bent ends 31^a of the latter.

The operation of the machine having been fully described in connection with the description of the construction thereof, no further description of the operation will be necessary to a complete understanding of the invention.

My invention, in its broader aspects, is not limited to the precise construction shown nor to the precise construction by which it may be carried into effect, as many changes other than those herein suggested may be made in such construction without departing from the main principles of the invention and without sacrificing the chief advantages thereof.

What I claim as new and desire to secure by Letters Patent, is:

1. In a device for presenting sheets to a moving sheet carrying member the combination with the sheet carrying member, of a sheet gripper, and a sheet positioning device, moving with said gripper, said gripper and said positioning device traveling with and while so traveling having a movement relatively to said sheet carrying member for adjusting the sheets upon the member.

2. In a device for presenting sheets to a moving sheet carrying member the combination with the sheet carrying member, of means for feeding the sheets to said member with an advancing movement, a sheet gripper, and a sheet positioning device moving with said gripper, said gripper and said positioning device traveling with and while so traveling having a movement relatively to said sheet carrying member for adjusting the sheets upon the member.
3. In a device for presenting sheets to a moving sheet carrying member the combination with a sheet carrying member, of means for advancing the sheet to said member at substantially the same speed as that of the member, a sheet gripper, and a sheet positioning device moving with said gripper, said gripper and said positioning device traveling with and while so traveling having a movement relatively to said sheet carrying member for adjusting the sheets upon the member.
4. In a device for presenting sheets to a moving sheet carrying member the combination with the sheet carrying member, of a sheet gripper and an abutment or gage carried by said gripper, said gripper and gage traveling with and while so traveling having a movement relatively to said sheet carrying member for adjusting the sheets upon the member.
5. In a device for presenting sheets to a moving sheet carrying member the combination with the sheet carrying member, of means for advancing the sheets to said member, a sheet gripper carried by said member, an abutment or gage carried by said gripper, and means for giving said gripper and gage a movement relatively to said sheet carrying member for adjusting the sheets upon the member while the latter is in motion.
6. In a device for presenting sheets to a moving sheet carrying member the combination with the sheet carrying member, of means for advancing the sheets to said member, at substantially the same speed as that of the member, a sheet gripper carried by said member, an abutment or gage carried by said gripper, and means for giving said gripper and gage a backward movement relatively to said sheet carrying member for adjusting the sheets upon the member while the latter is in motion.
7. In a device for presenting sheets to a rotary sheet carrying member the combination with a rotary member, of feed rollers for advancing the sheets to said member at substantially the same speed as that of the member, a sheet gripper carried by said member, an abutment or gage carried by said gripper, and means for giving said abutment or gage a backward movement relatively to said rotary member for adjusting the sheets upon the member while the latter is in motion.
8. In a device for presenting sheets to a moving sheet carrying member the combination with the sheet carrying member, of a combined sheet gripper and gage, and means for moving said gripper and gage in the path of the sheets and relatively to said sheet carrying member to adjust the sheets on the member while the latter is in motion and transversely to the path of the sheets to grip them and hold them in their adjusted position.
9. In a press for printing sheets, the combination with a member having an impression surface, of means for advancing the sheets to said member while the latter is in motion, said sheets being presented with their edges overlapping the forward edge of the impression surface, a combined sheet gripper and gage, and means for moving said gripper and gage toward the forward edge of the impression surface to adjust the sheets upon the impression surface while the said member is in motion and transversely to the path of the sheets to grip them and hold them in their adjusted position.
10. In a printing press, the combination with an impression cylinder having a plurality of recesses at the forward edge of the impression surface, of a gage consisting of a plurality of fingers adapted to enter the said recesses, and means for moving the said fingers rearwardly and forwardly with relation to the impression surface into and out of operative position in said recesses, substantially as described.

In testimony whereof, I have signed my name to this specification, in the presence of two subscribing witnesses.

GEORGE E. PANCOAST.
